BOX

John Walker Chalmers, Deptford, London, England, assignor to Molins Machine Company Limited, London, England

Application August 15, 1938, Serial No. 225,008
In Great Britain September 22, 1937

8 Claims. (Cl. 229—27)

This invention is for improvements in or relating to boxes, for example, to boxes adapted to contain cigarettes or other rod-shaped articles such as crayons.

5 Several embodiments of the invention will be described by way of example with reference to the accompanying drawings, in which:

Figure 1 is a plan of a one-piece blank from which a box is made.

10 Figure 2 is a perspective view of a box made from the blank shown in Figure 1, the lid being shown in an open position.

Figure 3 is a perspective view of a box made from two blanks one of which comprises an inner member, and shows the lid in an open position.

15 Figure 4 is a plan of one part of the blank from which the box shown in Figure 3 is made.

Figure 5 is a plan of a blank from which an inner member is formed.

20 Figure 6 is a perspective view of the inner member formed from the blank shown in Figure 5.

Figure 7 is a perspective view of a modified form of box provided with an inner member.

25 Figure 8 is a plan of a blank from which the receptacle and lid of the box in Figure 7 is formed.

Like reference numerals refer to like parts throughout the specification and drawings.

30 The boxes described herein are made from cardboard and referring to Figures 1 and 2, a box is made from a one-piece blank as shown in Figure 1. The blank when folded forms a box having, as can be seen from Figure 2, a relatively deep body portion with the opening at the top thereof and a lid. By the use of the term "relatively deep body portion" is meant that the depth of the body portion is great as compared with the distance from the front to the back of the box. The body portion and the lid are each of

35 oblong box-like form and of four-sided rectilinear shape in cross-section, and the front and back walls of the box are substantially parallel and form the longer sides of the oblong. The lid comprises a front lid panel 22, a back lid panel 23, a top panel 24 and side walls 25 and 26 which comprise overlapping side lid panels, the wall 25 being constituted by side lid panels 27 and 28 and the wall 26 being constituted by side lid panels 29 and 30. The back lid panel 23 is hingedly connected to a back body panel 20 by a hinge axis 21 which, as can be seen from Figure 2, is arranged at a position between the top and the bottom of the box.

40 From Figure 1 it will be seen that the side lid panels extend laterally from the front and back

lid panels and that the side lid panels 27 and 28 which are secured together to comprise the side wall 25 extend from the same side of the blank and that the side lid panels 29 and 30 which form the side wall 26 extend from the opposite side of the blank. The front lid panel 22 is reinforced by a panel 31 which is folded into engagement with the front lid panel and secured thereto. The portions of material indicated at 32 and 33 between the side lid panels 27 and 28 and the side lid panels 29 and 30 respectively can, if desired, be removed as waste material, but as shown in Figure 2, they are arranged as flaps and are folded into engagement with and secured to the inner surface of the top panel 24 of the box 15 so as to reinforce the top wall of the lid.

45 The body portion of the box comprises the back body panel 20 and a front body panel 34, a bottom panel 35 and side walls 36 and 37. The front body panel 34 has an overall length which is greater than the length of the back body panel 20, and the front body panel 34 is connected with the back body panel 20 by the bottom panel 35. The side walls 36 and 37 of the body portion comprise overlapping side body panels, the wall 36 being formed by side body panels 38 and 39 while the side wall 37 is constituted by side body panels 40 and 41. When the blank is folded the side body panels 38 and 40 which are of greater length than the length of the side body panels 39 and 41 are preferably arranged to be on the outside of the box, as can be seen from Figure 2, in order to give the box a neat appearance. The panels 39 and 41 could, however, be arranged on the outside of the box. It will, of course, be appreciated that when the box is closed the sides of the box are constituted by the side walls 25, 36 and 26, 37.

50 The portions of material indicated at 42 and 43 between the side panels 38 and 39 and 40 and 41 respectively and which extend laterally from the bottom panel 35 can, if desired, be removed as waste material, but preferably the portions 42 and 43 are arranged as flaps which are folded into engagement with and secured to the inner surface of the bottom panel 35 to provide a reinforcement therefor. From Figure 1 it will be seen that the side panels 38 and 40 and 39 and 41 extend laterally from the front and back body panels respectively, and that the side panels 38 and 39 which are secured together to form the side wall 36 extend from the same side of the blank and that the side panels 40 and 41 extend from the opposite side of the blank.

55 The top of the body portion is arranged at dif-

ferent heights to facilitate access to the contents. This can be seen from Figure 2 where the score line 21 which forms the hinge axis provides the top of the back body panel 20 and a portion 44 of the front body panel 34 is removed so that a part of the top of the front body panel terminates at the line 340 whilst portions 341 and 342 are left. Thus the top of the back body panel and a part of the top of the front body panel are both below the tops of the side walls of the body portion, so that when the box is opened it is possible to obtain access to the contents of the box from opposite sides thereof.

The junctions between the side walls 36 and 37 and the front wall 34 of the body portion comprise corner portions 45 and 46 at the top of the body portion of the box and the corner portions extend for a substantial distance above the hinge axis 21 and engage the inner surfaces of the front corners of the lid when closed and resist the opening of the lid. The front corners of the lid are constituted by the junction between the side and front walls of the lid. Thus one front corner of the lid lies at the junction between the walls 22 and 25 and the other front corner lies at the junction between the walls 22 and 26. As shown in the drawings the side walls 36 and 37 are of substantially the same length as the length of the articles to be contained in the box and the tops of the corner portions are, when the box is closed, in close proximity with the top of the lid. The lid when closed fits over the side and front walls of the body portion and covers the cut-away portion 44 in the front panel 34 so that the contents of the box are completely enclosed within the box.

In an alternative construction the parts 341 and 342 could be removed in addition to the portion 44. In this case the corner portions will be constituted by the front edges and the side faces of the side walls 36 and 37. This construction is, however, weaker than the construction in which the portions 341 and 342 are retained and is, therefore, not so desirable.

The front lid panel 22 is so dimensioned that during closing of the lid the free edge of the front panel or wall of the lid passes clear of the tops of the corner portions and of the front wall of the body portion, and the tops of the side walls 36 and 37, together with the contents of the box, are arranged within the surfaces swept out by the leading edges 47 and 48 of the side walls 25 and 26 respectively of the lid. In arranging that the corner portions shall extend for a substantial distance above the hinge axis 21 the latter is disposed between the top and the bottom of the body portion and the distance between the hinge axis 21 and the inside free edge 49 of the front wall 22 of the lid is greater than the distance between the hinge axis and front of the tops of the corner portions and the latter distance is in turn greater than the shortest distance between the hinge axis 21 and the inner surface of the front wall 22 of the lid.

Referring to the modified construction shown in Figures 3, 4, 5 and 6 the box is made from two blanks the first of which is shown in Figure 4 and is in many respects similar to the blank described with reference to Figure 1. The blank shown in Figure 4 when folded comprises the lid of the box and a receptacle while the blank shown in Figure 5 comprises an inner member which is inserted into the receptacle and constitutes together with the receptacle, the body portion of the box. The receptacle into which the blank

shown in Figure 5 is inserted is formed by the back panel 20 and the bottom panel 35 of the box, and it is completed by a front panel 50 for the receptacle and side walls for the receptacle. The side walls for the receptacle are constituted by side panels 51, 52, 53 and 54. The side panels 51 and 52 which extend from the same side of the blank are folded into overlapping engagement with each other and secured together and the side panels 53 and 54 which extend from the opposite side of the blank are also folded into overlapping engagement with each other and secured together. The front panel 50 is shorter than the back panel 20, so that when the receptacle is formed by folding the blank the top of the front panel is, as can be seen from Figure 3, below the level of the top of the back panel 20 as defined by the hinge axis 21.

As stated above, the body portion of the box shown in Figure 3 includes the blank shown in Figure 5 which blank comprises three parts. The two outer parts 55 and 56 are connected by a middle part which, as shown in Figure 5, comprises four panels 57, 58, 59 and 60. The panels 59 and 60 are folded as shown in Figures 3 and 6 to provide, when the inner member is inserted into the receptacle as shown in Figure 3, a partition between the front and back walls of the box. The panels 57 and 58 together extend from side to side of the receptacle. The parts 55 and 56 together with the side walls of the receptacle comprise the side walls 36 and 37 of the body portion of the box and the middle part as constituted by the panels 57 and 58 together with the wall 50 of the receptacle comprises the front wall of the body portion. From Figure 3 it will be seen that the inner member when folded and inserted into the receptacle, projects beyond the top edges of the receptacle and the corner portions of the box over which the lid fits are constituted by the junctions between the parts 55 and 56 and the middle part of the inner member. The overall length of the inner member is equal to the overall length of the body portion of the box so that the corner portions extend for a substantial distance above the hinge axis and a part of the top edge of the middle part of the inner member is arranged at a level which is lower than the remainder of the top edge of the inner member, so that when the latter is inserted into the receptacle to complete the body portion of the box, access may be obtained to the contents of the box when open from opposite sides of the box.

It will be appreciated that if it is not desired to provide a partition in the box the middle part of the inner member may comprise one panel which connects the outer parts 55 and 56.

If desired the outer parts 55 and 56 of the inner member are provided with slits 61 and 62 which extend lengthwise of the inner member and which, when the blank from which the inner member is formed is folded, provide projections 63 and 64 (see Figure 6) which project laterally from the front wall of the body portion of the box and which engage the side walls 25 and 26 of the lid when closed for the purpose of resisting the opening of the box.

Referring to the construction shown in Figures 7 and 8, it will be seen that the box comprises, as did the box previously described with reference to Figure 3, a body portion and a lid each of oblong box-like form and four-sided rectilinear shape and cross-section, with the front and back walls substantially parallel and forming the longer sides of the oblong. The cross-section of the box, 75

however, is trapezoidal and the arrangement is such that the angles formed between the back wall of the box and the side walls of the box are obtuse angles, while the angles formed between the front wall of the box and the side walls of the box are acute angles. The path swept out by the leading edges 47 and 48 of the side walls of the lid during closing of the lid is, in this construction, a substantially conical path, and in order that the box shall be closed it is, as described before, necessary that the tops of the side walls of the body portion and the contents of the box are arranged within the surfaces swept out by the leading edges 47 and 48.

15 It will be appreciated that if desired the blank shown in Figure 1 can be suitably modified so that when folded a box of trapezoidal cross-section is obtained from the one-piece blank.

20 In each of the constructions described above the angles which have been formed between the back wall of the box and the side walls of the box have comprised at least 90°. It is however, possible that in some instances the angle formed between the back wall of the body portion of the box and the side walls thereof may be less than 90°, but in such cases it is necessary, in order that the lid may be closed, to ensure that the tops of the side walls of the body portion and the contents of the box are arranged within the 25 surface swept out by the leading edges of the side walls of the lid otherwise it will not be possible to close the lid without causing damage to the box or the contents.

25 If desired, the boxes described with reference to Figures 3 to 8 inclusive may be provided with a liner 69, for example, a liner of aluminium or other metal foil, and the liner is disposed within the box and arranged to line the back and bottom walls of the box, and a part 70 of the liner 40 is disposed between the front wall 50 of the receptacle and the middle part of the inner member so that the liner is retained in position within the box. If desired, the liner may be arranged to lie against the back and top walls of the lid, 45 so that when the box is closed there is provided a liner which extends substantially around four adjoining inner sides of the box and includes the top and bottom of the box.

30 A picture or coupon or the like 71 may be included in the box and may, as shown in Figure 3, be conveniently included between the front wall of the receptacle and the part 70 of the liner.

35 What I claim as my invention and desire to secure by Letters Patent is:

35 1. A box of oblong rectilinear shape in cross-section made of cardboard or other like material with the front and back walls of the box substantially parallel and forming the longer sides of the oblong, said box comprising a relatively 40 deep body portion with the opening at the top thereof, a boxlike lid whose back wall is hingedly connected to the back wall of the body portion at a position between the top and bottom of the box and corner portions at the top of the body portion which corner portions extend for a substantial distance above the hinge axis of the lid and engage the front corners of the lid when closed to resist opening of the lid, said corner portions, together with the contents of the box, being 45 arranged within the surfaces swept out by the leading edges of the side walls of the lid during closing of the latter, the front wall of the lid being so dimensioned that during closing of the lid the free edge of such front wall passes clear of the tops of said corner portions and of the front 50

wall of the body portion, while the front corners of the lid, when the latter is closed, extend downwardly below the hinge axis of the lid.

55 2. A box of oblong rectilinear shape in cross-section made of cardboard or other like material with the front and back walls of the box substantially parallel and forming the longer sides of the oblong, said box comprising a relatively deep body portion with the opening at the top thereof, the top of the body portion being arranged at different heights to facilitate access to the contents of the box, a boxlike lid whose back wall is hingedly connected to the back wall of the body portion at a position between the top and bottom of the box and corner portions at the top of the body portion, which corner portions extend for a substantial distance above the hinge axis of the lid and engage the front corners of the lid when closed to resist opening of the lid, said corner portions, together with the contents of the box, being arranged within the surfaces swept out by the leading edges of the side walls of the lid during closing of the latter, the front wall of the lid being so dimensioned that during closing of the lid the free edge of such front wall passes clear of the tops of said corner portions and of the front wall of the body portion, while the front corners of the lid, when the latter is closed, extend downwardly below the hinge axis of the lid.

60 3. A box of oblong rectilinear shape in cross-section made from a single blank of readily foldable material such as cardboard, with the front and back of the box substantially parallel and forming the longer sides of the oblong, said box including front and back lid panels separated by a top panel and side lid panels to complete the lid, a front body panel the top of which is arranged at different heights, a back body panel, a bottom panel separating the back body panel from the front body panel and side body panels to complete the body portion of the box, the back lid panel being hingedly connected with the top of the back body panel while at the top of the body portion the junctions formed by the front body panel and the adjoining side body panels form corner portions which extend for a substantial distance above the hinge axis of the lid and engage the front corners of the lid when closed to resist opening of the lid, said corner portions together with the contents of the box, being disposed within the path swept out by the leading edges of the side panels of the lid during closing of the latter, while the front lid panel is so dimensioned that during closing of the lid the free edge of the front lid panel passes clear of the tops of said corner portions and of the front body panel, while the front corners of the lid, when the latter is closed, extend downwardly below the hinge axis of the lid.

65 4. A box of oblong rectilinear shape in cross-section made of cardboard or other like material with the front and back walls of the box substantially parallel and forming the longer sides of the oblong, said box comprising a relatively deep receptacle with the opening at the top thereof, a boxlike lid whose back wall is hingedly connected to the back wall of the receptacle at a position between the top and bottom of the box, the receptacle and the lid being formed by folding a single blank, and an inner member fitted within the receptacle to reinforce the latter and to provide corner portions which extend for a substantial distance above the hinge axis of the lid and which engage the front corners of the lid

when closed to resist opening of the lid, said corner portions, together with the contents of the box, being arranged within the surfaces swept out by the leading edges of the side walls of the lid during closing of the latter, the front wall of the lid being so dimensioned that during closing of the lid the free edge of such front wall passes clear of the tops of said corner portions and of the front wall of the body portion, while the front corners of the lid, when the latter is closed, extend downwardly below the hinge axis of the lid.

5. A box of oblong rectilinear shape in cross-section made of cardboard or other like material with the front and back walls of the box substantially parallel and forming the longer sides of the oblong, said box comprising a relatively deep receptacle with the opening at the top thereof, a boxlike lid whose back wall is hingedly connected to the back wall of the receptacle at a position between the top and bottom of the box, the receptacle and the lid being formed by folding a single blank, and an inner member fitted within the receptacle to reinforce the latter and to provide corner portions which extend for a substantial distance above the hinge axis of the lid and engage the front corners of the lid when closed to resist opening of the lid, said corner portions, together with the contents of the box, being arranged within the surfaces swept out by the leading edges of the side walls of the lid during closing of the latter, the front wall of the lid being so dimensioned that during closing of the lid the free edge of such front wall passes clear of the tops of said corner portions and of the front wall of the body portion, while the front corners of the lid, when the latter is closed, extend downwardly below the hinge axis of the lid, and a lateral projection from the front wall of the body which engages a side wall of the lid when closed to resist opening of the lid, said projection being formed by a slit extending lengthwise of the box and formed in a side wall at a position adjacent the junction of the side wall with the front wall of the box.

6. A box made of cardboard or other like material, said box being of trapezoidal shape in cross-section with the longer sides parallel and the shorter of the longer sides forming the back of the box and including a relatively deep body portion with the opening at the top thereof, a boxlike lid whose back wall is hingedly connected to the back wall of the body portion at a position between the top and bottom of the box and corner portions at the top of the body portion, which corner portions extend for a substantial distance above the hinge axis of the lid and engage the front corners of the lid when closed to resist opening of the lid, said corner portions, together with the contents of the box, being arranged within the surfaces swept out by the leading edges of the side walls of the lid during closing of the latter, the front wall of the lid being so dimensioned that during closing of the lid the free edge of such front wall passes clear of the tops of said corner portions and of the front wall of the body portion, while the front corners of the lid, when the latter is closed, extend downwardly below the hinge axis of the lid.

7. A box of oblong rectilinear shape in cross-

section made of cardboard or other like material with the front and back walls of the box substantially parallel and forming the longer sides of the oblong, said box comprising a relatively deep body portion with the opening at the top thereof, a boxlike lid whose back wall is hingedly connected to the back wall of the body portion at a position between the top and bottom of the box, corner portions at the top of the body portion which corner portions are each constituted by the front wall and an adjoining side wall of the body portion and extend for a substantial distance above the hinge axis of the lid and engage the front corners of the lid when closed to resist opening of the lid, said corner portions, together with the contents of the box, being arranged within the surfaces swept out by the leading edges of the side walls of the lid during closing of the latter, the front wall of the lid being so dimensioned that during closing of the lid the free edge of such front wall passes clear of the tops of said corner portions and of the front wall of the body portion, while the front corners of the lid, when the latter is closed, extend downwardly below the hinge axis of the lid, and a lateral projection from the front wall of the body which engages a side wall of the lid when closed to resist opening of the lid, said projection being formed by a slit extending lengthwise of the box and formed in a side wall at a position adjacent the junction of the side wall with the front wall of the box.

8. A box of oblong rectilinear shape in cross-section made of cardboard or other like material with the front and back walls of the box substantially parallel and forming the longer sides of the oblong, said box comprising a relatively deep body portion with the opening at the top thereof, the top of the body portion being arranged at different heights to facilitate access to the contents of the box, a boxlike lid whose back wall is hingedly connected to the back wall of the body portion at a position between the top and bottom of the box, corner portions at the top of the body portion, which corner portions are each constituted by the front wall and an adjoining side wall of the body portion and extend for a substantial distance above the hinge axis of the lid and engage the front corners of the lid when closed to resist opening of the lid, said corner portions, together with the contents of the box, being arranged within the surfaces swept out by the leading edges of the side walls of the lid during closing of the latter, the front wall of the lid being so dimensioned that during closing of the lid the free edge of such front wall passes clear of the tops of said corner portions and of the front wall of the body portion, while the front corners of the lid, when the latter is closed, extend downwardly below the hinge axis of the lid, and a lateral projection from the front wall of the body which engages a side wall of the lid when closed to resist opening of the lid, said projection being formed by a slit extending lengthwise of the box and formed in a side wall at a position adjacent the junction of the side wall with the front wall of the box.

JOHN WALKER CHALMERS.
